DESIGN FOR A FOUNTAIN PEN

Lynn P. Martin and Wilbur K. Olson, Fort Madison, Iowa, assignors to W. A. Sheaffer Pen Company, Fort Madison, Iowa, a corporation of Delaware

Application October 30, 1941, Serial No. 103,962

Term of patent 14 years

To all whom it may concern:

Be it known that we, Lynn P. Martin and Wilbur K. Olson, citizens of the United States, residents of Fort Madison, in the county of Lee and State of Iowa, have invented a new, original, and ornamental Design for a Fountain Pen, of which the following is a specification, reference being had to the accompanying drawing, forming a part thereof.

Figure 1 is a front elevational view of a fountain pen showing our new design, the cap thereof being disposed on the writing point end;

Fig. 2 is a side elevational view of the fountain pen shown in Fig. 1 with the cap removed from the writing point end and disposed on the opposite end; and

Fig. 3 is a front elevational view of the fountain pen shown in Fig. 2.

We claim:

The ornamental design for a fountain pen, substantially as shown and described.

LYNN P. MARTIN.
WILBUR K. OLSON.
